UNITED STATES PATENT OFFICE.

JOSEPH SOTY, OF NEW YORK, N. Y.

DISMOUNTABLE AND ADJUSTABLE SKATE.

1,142,855.

Specification of Letters Patent. Patented June 15, 1915.

Application filed January 27, 1915. Serial No. 4,665.

To all whom it may concern:

Be it known that I, JOSEPH SOTY, a subject of the Emperor of Austria-Hungary, residing at New York, in the county of New York and State of New York, have invented new and useful Improvements in Dismountable and Adjustable Skates, of which the following is a specification.

My invention relates to dismountable and adjustable skates and has as its principal object to provide skates the component parts of which may easily be separated from each other and be reassembled, without the use of tools, the advantages of which are that the skates taken apart, may easily be carried in a pocket and that different kinds of blades, serving for different modes of skating, may be used with the same body portion of a skate.

20 A further object of my invention is to provide skates which adapt themselves to various distances of toes to heels and may either permanently be attached to the shoes by means of screws or be provided with 25 gripping means automatically adapting themselves to the various sizes of shoes. One advantage of the latter feature is that the skates may easily and quickly be attached to and detached from the shoes.

30 A final object of my invention is to provide skates of the character described which are of comparatively simple and solid construction and cheap to manufacture.

Reference will now be had to the accompanying drawings in which:

Figure 1 is a perspective view of a skate adapted to be readily attached to and detached from the shoe. Fig. 2 is a perspective view of a skate destined to be permanently attached to the shoe. Fig. 3 is a perspective view of a skate of different design, showing the blade detached from the body portion. Figs. 4 and 5 are vertical cross sectional views, taken on the lines 4—4 and 5—5 of Figs. 1 and 3, respectively, the latter being considered in its assembled form. Figs. 6, 7 and 8 are vertical cross sectional views of differently shaped blades, showing, in elevation, fractions of the respective body portions engaging same. Figs. 9, 10 and 11 are perspective views of differently shaped blades detached from the body portions of the skates. Fig. 12 is a perspective view of

a fastening attachment. Fig. 13 is a longitudinal horizontal section of another attachment.

The same part is designated by the same reference character throughout the different views.

Referring more particularly to the drawing, 15 designates the sole plate, 16 the heel plate, 17 the vertical stay members and 18 the channel shaped clamping members of the body portion of each skate which is substantially the same in all forms of my device, with the exception that in Figs. 3 and 5 I show a form in which there is an extra tube 19 formed in the clamping members 18, for purposes which will hereinafter be set forth.

It will be seen, that the body portion of each skate comprises a heel portion consisting of the heel-plate 15, its respective stay member 17 and clamping member 18, and a sole-portion, consisting of the sole-plate 16, 75 its respective stay member 17 and clamping member 18, an additional stay member 17^a being added at the front end. Thus the heel and sole portions of the body of the skate are entirely separate units, connected only by the blades 20 which are so shaped that they may be inserted into and be engaged by the channel or groove 21 formed in the clamping members 18 of both the heel and the sole portions of the body of the skate. 80

The channels or grooves 21 and the corresponding parts of the blades 20 are preferably of a standard cross sectional area so that any blade may fit into the clamping members of any skate made according to my invention, thus being thoroughly interchangeable. The blades 20 are slideable longitudinally in the clamping members 18, a flange 22 being formed at the front end of that part of the blades 20 which enters the groove 21, in order to limit this sliding movement of the blades in one direction and a lug 23 carried by the front end of the blades 20, adapted to be engaged by a clamping hook 24 hingedly carried by the stay 17^a, serves to limit the said sliding movement in the opposite direction. The heel portion of the body of the skates slides freely on the blade fixed to the sole portion as above described and is maintained at its proper place by being attached to the shoe.

heel. It will be seen that on account of this construction the skates made according to my invention easily adapt themselves to various distances of the soles from the heels.

5 The skates are adapted to be permanently attached to the shoes by means of screws passed through screwholes 25 made in the sole and heel plates, in the usual way, clamps 26 and 27 at the front end of the sole plate 15 and rear end of the heel plate 16, respectively, being provided for the sake of additional security. The point of the clamp 26 overlaps and engages the protruding edge of the sole, whereas that of the clamp 15 27 enters a hole to be made for that purpose in the back of the heel.

If it is desired to adapt the skates for being temporarily attached to the shoes, so as to take them off after each use, I provide a 20 resilient clamp 28 (Figs. 1 and 18), consisting of a tube 28^a, a helical spring 28^b in the center of the tube 28^a, two plungers 28^c one in either end of the tube 28^a, their inner ends being secured to the spring 28^b and their 25 outer ends carrying hooks 28^d. The plungers 28^c are provided, near their outer ends, with lugs 28^e for limiting their movement in respect to the tube 28^a. The hooks 28^d are hooked into slots 29 formed in each of the 30 stays 17, and thereby tend to draw the heel and sole portions of the body of the skate toward each other, that movement being limited by the clamps 26 and 27 engaging the shoe sole and heel, respectively, whereby the 35 skate automatically adapts itself to the length of the shoe. I attach two other clamps 30, one to the sole and one to the heel-portion of the body of the skate. These clamps consist of a tube 30^a, a helical spring 30^b inserted therein and plungers 30^c, sliding in the tube 30^a, one at each end, attached to the 40 spring 30^b, having integrally formed thereon clamps 30^d adapted to engage the sole and heel of the shoe, respectively, in the same way as described with regard to the clamps 26 and 27. The tube 30^a is slotted transversely at its longitudinal center, as at 30^e (Fig. 12) for taking up and engaging therein 45 projections 30^f depending from the top of the slots 29 formed in the stays 17; and longitudinally at the bottom of each end, as at 30^g (Fig. 4) to receive therein lugs 30^h depending from the plungers 30^c which serve 50 to guide the plungers and also to seize them thereby with the thumbs and fingers, thus stretching the clamp in opposition to the springs 30^b. When the lugs 30^h are released, the clamps 30 grip the sole and heel of the 55 shoe automatically. Thereby, it will be seen, my skates may be attached to shoes of different widths without screwing, cranking or any other mechanical operation.

In Figs. 3 and 5 I show a form of my device in which the sole and heel portions 60 of the body of the skate are permanently

connected together by means of a pin 31 inserted into the tube 19 of the heel portion of the clamping member 18 having a knob 31^a at its rear end, and attached at its fore end to a helical spring 31^b the other end of which is fastened in the fore end of the tube 19 of the sole portion of the clamping member 18, by the hook 24 drawn through it. The operation of this device is obvious from the drawing and requires no further description.

In Fig. 9 I show a blade adapted for fancy-skating, in Fig. 10 a racing-skate blade and in Fig. 11 a blade for an ice-hockey skate.

Figs. 6, 7 and 8 also show some varieties of shapes of blades adapted for different requirements of the skating sport.

It is obvious that besides these many other shapes may be manufactured and used in conjunction with the body-portion of my skates, thus adapting same for universal use. Also, if the blade breaks, which is often the case with fine steel blades, the body portion of the skate can still be used.

It will be understood that while I have thus shown and described some preferred forms of embodiment of my invention, I do not want to be limited to its mechanical details but may resort to alterations and modifications which come within the scope of the claims hereunto appended.

I claim,

1. Skates with interchangeable runners comprising, in combination, shoe-supporting members adapted to be removably attached to the sole and heel of a shoe, runners of different types adapted to serve the purposes of various modes of skating and means carried by said shoe-supporting members for interchangeably attaching thereto either one of said runners.

2. Skates comprising, in combination, a sole and heel plate adapted to be attached to the respective portions of a shoe, stays depending from said sole and heel plates, gripping means formed on said stays, and blades adapted to be removably inserted into and be engaged by said gripping means.

3. Skates with interchangeable runners comprising, in combination, separate heel and sole plates attachable to the respective portions of a shoe, vertical stays depending from said heel and sole plates, longitudinal portions carried by the lower end of said stays, a cylindrical bore provided throughout the length of each of said longitudinal portions, a spiral spring inserted in the bore corresponding to the sole plate, a rod slideable in the bore corresponding to the heel plate connected to said spring with one end, having means at its other end preventing it from slipping out of the bore, gripping means formed in said longitudinal portions below said bores, and interchangeable runners adapted to be inserted into and engaged by said gripping means.

4. Skate runners of different longitudinal and cross sectional shape adapted for the purposes of various modes of skating, means on said runners for alternately attaching them to or detaching them from the body-
5 portions of skates, and means provided on said body-portions for removably attaching

thereto either one of said runners, substantially as and for the purpose set forth.

JOSEPH SOTY.
